WINDOW FRAME AND ROLLING SCREEN

David Gorgun, Brooklyn, N. Y.

Application January 31, 1946, Serial No. 644,630

(Cl. 160—239)

1 1966

This invention relates to window screens and more particularly to a rollable window screen.

An object of this invention is to form a window screen closure which is adjustable and easily openable.

Another object is to form a rollable window screen which will rest securely in position and provide a tight fit between the screen and its framework.

A further object is to form a rollable, flexible window screen closure in which the screening material can be easily and simply replaced.

Another object is to form a rollable window screen closure which can be easily and quickly installed in a window opening or permanently inserted in a building during its construction.

A further object is to provide a rollable, flexible window screen in a framework, the screening being slidable in guides in the framework to permit an opening of any desired size.

A still further object is to provide a screen structure which is not necessary to move when opening and closing the windows, and which need not be taken down in the fall of the year, thus providing a convenience not found in the average screen construction.

These and other objects are accomplished by forming a framework whose side elements are provided with guideways through which retaining rods extend and by providing above the framework a roller holding one end of a flexible mesh screening sheet. The side edges of the sheet extend in the guideways and are provided with gripping means which coact with the retaining rods to slidably secure the sheet cross the frame.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a new and novel screen shown attached to a building.

Fig. 2 is a sectional view along the line 2—2 of Fig. 1.

Fig. 3 is a horizontal sectional view along the line 3—3 of Fig. 2.

Fig. 5 is a perspective view of a detail showing

a roller and a sheet of screening material. Fig. 6 is a fragmentary sectional perspective

view showing a side element of a screening frame and a retaining rod inside the side element and secured to a sheet of screening.

In the drawings and in the specification in which like numbers indicate similar elements, a window screen 10 is comprised of a frame 11, retaining rods 12, roller 13, and a flexible screening sheet 14.

10 The frame 11 is formed of side members 15, a cross top member 16 and a cross bottom member 17 positioned to form a rectangle and each member secured at its end to its adjacent member. Each side member and the cross bottom member has a U-shaped cross section, the bottom of the U-shaped formation being a base section 18 and the sides of the U-shaped formation being the two legs 19. The legs 19, at approximately their mid point, are bent toward each other forming shoulders 20, and above the shoulders the legs are parallel 20 to each other forming a narrow guideway 21. The base section 18 and the adjacent portions of the legs and the shoulders 20 form a rectangular passageway 21^a through which the retaining rods 12 extend. One of the legs 19 of each member is provided with an extending flange 22 which projects beyond the base and in the direction of the leg.

The cross top member is provided with a longitudinally extending slot 23 longer than the width of the screen sheet 14 and through which the sheet extends. The side members are positioned with their guideways 21 facing each other and their flanges 22 positioned at the outside of the frame. The bottom member 17 is positioned with its guideway 21 facing upwardly and its flange 22 on the outside. The flanges of the bottom and the two sides thus form a continuously extending lip at the outer edge of the frame which rests against the outside wall of the building and through which nails 24 or other holding means extend retaining the frame in position in the window opening.

The legs of the cross bottom member 17 at their mid point are provided with a cutaway section 25 and the retaining rods 12, which meet at the same point are provided with a raised or bent section 26.

The roller 13 extends across the window opening above the cross top member 16 and is rotatably secured at its ends in the window frame work or building. The flexible screening sheet 14 is secured along one of its ends to the roller. Sides 21 of the sheet rest in the guideways 21 in the side elements and the edges are provided with hooks 28 or other catching means which slidably

grip and coact with the retaining rods 12 in the side elements to hold the sheet laterally extended. The hooks only partly encircle the rods and so detachably grip them. An end 29 of the sheet opposite the roller is provided with a hook 30 similar to the hooks 28, at its mid point, which is adapted to coact with the raised or bent section 26 of the rods to hold the sheet longitudinally extended.

A cover or closure 31 is rotatably held by the hinges 32 to the building or window frame in front of the roller and covers the space above the cross top member 16 thus completing the closure of the window opening.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A roller type closure device comprising a frame adapted to be inserted in a window, said frame having side members, a top member and a bottom member, said side members being channel-shaped in cross section with a wide base chamber and with their open sides opposed, said bottom member being channel-shaped in cross section with a wide base chamber and with its open side facing upwardly, said top member being vertically slotted between said side members, a roller above said top member, a flexible wire mesh screen secured at its top to said roller and extending into said side members and being adapted to extend into said bottom member, a U-shaped rod having its legs disposed in said side member base chambers and having its connecting yoke disposed in said bottom member base chamber, and hooks secured to the side edges of said screen for sliding on said rod legs for guiding said screen as it is rolled and unrolled.

2. A roller type closure device comprising a frame adapted to be inserted in a window, said frame having side members, a top member and a bottom member, said side members being channel-shaped in cross section with a wide base chamber and with their open sides opposed, said bottom member being channel-shaped in cross section with a wide base chamber and with its open side facing upwardly, said top member being vertically slotted between said side members,

a roller above said top member, a flexible wire mesh screen secured at its top to said roller and extending into said side members and being adapted to extend into said bottom member, a U-shaped rod having its legs disposed in said side member base chambers and having its connecting yoke disposed in said bottom member base chamber, and hooks secured to the side edges of said screen for sliding on said rod legs for guiding said screen as it is rolled and unrolled, each of said hooks having a straight shank and a semi-circular head.

3. A roller type closure device comprising a frame adapted to be inserted in a window, said frame having side members, a top member and a bottom member, said side members being channel-shaped in cross section with a wide base chamber and with their open sides opposed, said bottom member being channel-shaped in cross section with a wide base chamber and with its open side facing upwardly, said top member being vertically slotted between said side members, a roller above said top member, a flexible wire mesh screen secured at its top to said roller and extending into said side members and being adapted to extend into said bottom member, a U-shaped rod having its legs disposed in said side member base chambers and having its connecting yoke disposed in said bottom member base chamber, and hooks secured to the side edges of said screen for sliding on said rod legs for guiding said screen as it is rolled and unrolled, each of said hooks having a straight shank and a semi-circular head, said bottom member having an opening at one side thereof, and said connecting yoke having a bent-up portion opposite said opening, and a hook secured to the bottom edge of said screen for coacting with said bent-up portion for holding said screen in unrolled position.

DAVID GORGUN.
